W. E. PORTER.

STEM WINDING AND SETTING WATCH,
APPLICATION FILED SEPT. 30, 1908.

919,764.

Patented Apr. 27, 1909.

UNITED STATES PATENT OFFICE.

WILSON E. PORTER, OF NEW HAVEN, CONNECTICUT, ASSIGNOR TO NEW HAVEN CLOCK CO., OF NEW HAVEN, CONNECTICUT, A CORPORATION.

STEM WINDING AND SETTING WATCH.

No. 919,764.

Specification of Letters Patent.

Patented April 27, 1909.

Application filed September 30, 1908. Serial No. 455,507.

To all whom it may concern:

Be it known that I, WILSON E. PORTER, a citizen of the United States, residing at New Haven, in the county of New Haven and State of Connecticut, have invented a new and useful Improvement in Stem-Winding and Stem-Setting Watches; and I do hereby declare the following, when taken in connection with the accompanying drawings and the numerals of reference marked thereon, to be a full, clear, and exact description of the same, and which said drawings constitute part of this specification, and represent, in—

Figure 1 a view in rear elevation of a watch constructed in accordance with my invention, with the back-cap removed. Fig. 2 a broken view in inside elevation of the back movement-plate, the bridge being indicated by broken lines. Fig. 3 a broken edge view showing the dog in its relation to the main winding-wheel. Fig. 4 a broken plan view of the dog and its shaft. Fig. 5 a detached view in elevation of the dog.

My invention relates to an improvement in stem-winding and stem-setting watches, the object being to provide simple, durable and reliable means for preventing the main-spring from being wound too tight.

With these ends in view my invention consists in a stem-winding and stem-setting watch having certain details of construction and combinations of parts as will be herein-after described and pointed out in the claims.

In carrying out my invention as herein shown, I employ a disk-like dog 2 formed with a stop lug 3 and a relaxing tooth 4 located adjacent to the near end, as I may say, of the lug 3. The stop dog is mounted upon a rock shaft 5 journaled at one end in the front movement-plate 6 and at its opposite end in a bridge or supplemental plate 7 held in place by two of the screws 8 which secure the back movement-plate 9 to two of the pillars 10 of the movement. In other words, two of the screws which are employed to fasten the back movement-plate to the pillars, are also employed for securing the bridge in place. When in place the said bridge rests upon the back or outer face of the said back-movement plate.

The dog 2 is located so that the main winding-wheel 11 as it is turned in winding, rides over the lug 3 and tooth 4 of the dog which is returned to its normal position every time a tooth of the said wheel "snaps

over" it, by a spring 12 encircling the shaft 5 at one end, and at its other end wound about one of the pillars 10 of the movement. This spring however, may be constructed and arranged in a variety of ways as long as it is adapted to cause the dog to recover after a tooth of the winding-wheel 11 has passed over it. The said main winding-wheel 11 is meshed into by an intermediate winding-wheel 13 constantly engaged by a winding-pinion 14 fixed upon the inner end of a rotatable and longitudinally movable stem 15 located within the pendant 16 and furnished at its outer end with a winding crown 17. However the particular means employed for rotating the main winding-wheel has nothing to do with my present invention.

One end of the main-spring which is not shown, is connected with the main winding-wheel 11, while its opposite end is connected with the time-wheel 19 which meshes into the center pinion (not shown) of the time-train. It will be understood that in winding the main-spring, the teeth of the wheel 11 ride over the tooth 4 of the dog 2 and effect a constant oscillation of the dog in conjunction with the spring 12 before mentioned.

When winding pressure is taken off the crown 17, the main-spring immediately asserts itself and turns the wheel 11 in the reverse direction, whereby the tooth of the said wheel which is at the time in front of the relaxing tooth 4 of the dog 2, immediately turns the dog from left to right, and thus jams the lug 3 of the dog into the adjacent teeth of the wheel so as to lock and hold the wheel against further reverse rotation. This locking engagement of the lug 3 of the dog 2 with the teeth of the wheel 11 does not, however, take place until after the said wheel has been reversely rotated for a short distance—for a distance sufficient to relax the tension upon the winding spring to the degree required for preventing it from breaking. This construction also avoids the "over-banking," as it is termed, of the balance-wheel of the watch, resulting from an excess of pressure upon the time-train due to overwinding the main-spring and causing the movement to run too fast until this over-pressure has spent itself. By employing two or more relaxing teeth 4 instead of one, as shown, the lug 3 would be carried farther out of range of the teeth of the wheel 11 and consequently would permit a greater reverse rotation of the same before

its reengagement therewith and arrest thereof, whereby a greater relaxation of the winding spring would be effected. However I have found the employment of one relaxing tooth 4 close to the near end of the lug 3 sufficient to prevent over-winding.

As shown, the disk-like dog 2 is formed with a narrow radial slot 20 arranged to be exposed through a cut 21 in the movement-plate 9 so that at any time that it is desired to let the spring down any convenient instrument, such as the end of a small screw-driver, might be inserted into the slot 20 and the dog turned against the tension of its spring 12 so as to disengage its lug 3 and tooth 4 from the teeth of the main winding wheel 11 and permit the same to be reversely rotated until the spring has been unwound.

It will be observed that the back movement-plate is cut away under the bridge or supplemental plate 7 so as to permit the main winding-wheel 11 and the dog 2 to be located in the plane of the back movement-plate.

25 I claim:—

1. In a stem-winding and stem-setting watch, the combination with the front and back movement-plates thereof, of a bridge bearing upon the back or outer face of the 30 said back movement-plate, a main winding-

wheel, a rock-shaft having its respective ends journaled in the said bridge and front movement-plate, a spring-actuated oscillating dog mounted upon the said rock-shaft and located between the said front movement-plate and bridge in position to bear against the inner face of the said bridge, and the said dog being formed with a stop-lug and a relaxing-tooth for coaction with the teeth of the said wheel.

2. In a stem-winding and stem-setting watch, the combination with the movement-plates thereof, of a main winding wheel, a spring-actuated oscillating disk-like dog located between the said plates and provided with a stop-lug and a relaxing-tooth and formed with an operating slot for the reception of an instrument by means of which the dog may be manually operated for the reverse rotation of the main winding-wheel, 50 and a shaft upon which the dog is mounted, the ends of the said shaft being carried by the respective movement plates.

In testimony whereof, I have signed this specification in the presence of two subscribing witnesses.

WILSON E. PORTER.
